FILE OR FOLDER CLIP

Louis G. Mayer and Forest J. Neel, Louisville, Ky., assignors, by direct and mesne assignments, to The Dura-Clip Co., Louisville, Ky., a corporation of Kentucky

Application April 13, 1948, Serial No. 20,744

1 Claim. (Cl. 24—153)

1

This invention relates to file or folder clips, and particularly to the type in which a pair of clamping arms which are interconnected are made with a projecting tongue upon one which extends through an aperture in the other to hold the arms clamped together.

The main object of our invention is to provide a file or folder clip which is of such rugged construction that it will form a permanent fastening means upon a file or folder for firmly securing the documents slipped or introduced under either clamping arm thereof.

Another object is to provide a file or folder clip of the character indicated which may be cadmium plated or parkerized to present a smooth finish and form a permanent part of a case file.

Another object, again, is to have such a file or folder clip which is stamped from a single sheet of metal and folded at an intermediate narrow portion to result in a pair of substantially coextensive equal arms for primarily securing the clip on a file and clamping papers and documents frictionally against either or both sides of the file, the free ends of both arms being bent slightly outward to facilitate sliding the papers under the arms on the file.

A further object is to provide a clip of this type which is so simple in form and easy to manufacture as to encourage general adoption by the public everywhere.

It is likewise an object to provide a clip which may be made in particularly large sizes capable of being permanently attached to a large file or folder and receiving a considerable number of papers and the like under each clamping arm thereof.

Other objects and advantages of our invention will appear in further detail as the specification proceeds.

In order to bring out the features of the invention comprehensively, the latter is illustrated on the accompanying drawing forming part hereof, and in which:

Figure 1 is a plan view of a sheet metal blank when stamped out to form the present clip and embodying the invention in a practical form;

Figure 2 is a front elevation or obverse view of the clip when in position upon a file and frictionally retaining a paper or documents introduced beneath one clamping arm thereof;

Figure 3 is a reverse view of the same clip when in place upon the mentioned file or folder;

Figure 4 is a side elevation of the clip and shows the latter as seen from the right in Figure 2;

Figure 5 is a vertical section through the clip as taken on line 5—5 in Figure 2;

2

Figure 6 is a transverse section taken on line 6—6 in Figure 4, showing details.

In the various views, the same reference numerals indicate the same or like parts.

5 In modern business, it is common practice to secure papers and files together by various kinds of clips and fastening means, some simple forms made of wire being the most common, but in many cases the clips are obviously mere makeshifts so as to serve temporarily and soon weaken only to allow papers to fall off the files which are supposed to retain them. On the other hand, fasteners that extend through a file or folder and all papers contained therein are inconvenient to handle when papers are to be added to or withdrawn from such a file.

Upon considering this problem, we have found it possible to design a special file or folder clip which is capable of being permanently secured 20 upon the file or folder once the clip has been properly affixed thereto, and serving to receive or release papers slipped under the arms thereof, as will now be definitely described.

Hence, in the practice of our invention, and 25 referring again to the drawing, the paper file or folder clip embodying our invention is preferably stamped from sheet metal to form a blank shown in Figure 1, in which the two clamping arms 7 and 8 are joined by a narrow neck portion 9, while the free ends 10 and 11 of the clamping arms are slightly bent out of the plane of the 30 clamping arms to facilitate placing the clip on the file or folder 12 intended to be equipped therewith and holding papers and documents to be 35 assembled with or upon the file, as indicated in broken lines 13, 13. The narrow or neck portion 9 may be preformed or bent at the time the clip is placed in position upon the documents or file to form the curved portion 14 which connects 40 the two arms and envelops the upper edge 15 of the file or folder 12. In order to facilitate not only the handling of the clip and placing it in position on the file, but especially the introduction of papers and documents beneath arms 7 and 8, the free ends 10 and 11 thereof are well 45 rounded, while at the upper ends where the arms connect with neck portion 9, shoulders 16 and 17 of the arms are also rounded so that no sharp corners exist anywhere on the clip. Furthermore, 50 both clamping arms 7 and 8 are preferably bowed outwardly, as especially shown in Figures 4 and 5, to facilitate holding a maximum number of sheets or documents between the same and folder 12. In order to stiffen the arms a little, they may 55 also be transversely curved throughout, as shown

in Figure 6, which also improves their grip on papers held thereby.

In the upper portion of clamping arm 7 is stamped an upwardly-directed tongue 18 which in use is bent at a right angle inwardly toward clamping arm 11 and is directed through a hole 19 in a corresponding position in said arm 11, as indicated in broken lines at 20 in Figure 4. When the tongue is pressed through to enter the aperture 19 in the arm 8, it leaves an aperture 21 in the arm 7 from which it extends, and, projecting through the aperture or hole 19, it is bent up into the position shown in Figures 4 and 5, to lie upon the outer face of arm 8 and thus clamp arms 7 and 8 in permanent association with file or folder 12 so that upper edge 22 thereof extends up into bent portion 14 of the clip, while tongue 18 extends through a perforation in the file which may either be previously punched or simply formed by pushing the tongue through said file at the time the clip is placed in position thereon.

The upper portions 23 and 24 of arms 7 and 8 above the level of the tongue 18 are, of course, merely clamped upon the file or folder 12, the tongue having, as it were, a bridge connection 25 extending through the file and serving as a stop for the papers or documents 13, 13 which may be slid or pushed up under the clamping arms, either or both, as the case may be, up to the mentioned bridge portion or stop. For this reason, the papers may be replaced, removed altogether or have further papers added at any time to the file, the papers being solely retained by friction. In order to ensure the effective action of the clamping arms, they are, of course, made sufficiently large and strong to provide a powerful clamping action. While various sizes of clips may be made, we have found that sheet metal varying from about 20 to 26 gauge serves quite well, and suggest a practical size of clip blank which may be made from a strip of such metal about $\frac{7}{16}$ of an inch wide and about $4\frac{1}{2}$ inches long to result in an over-all length of about $2\frac{1}{4}$ inches when the blank is bent double to form the clip. These dimensions merely refer to one size and we are naturally not limited thereto or to any other size of clip.

From the foregoing, it is evident that if the clip is made approximately of the size shown in the drawing, or in a size approaching that shown, it will be very strong so that when it is fixed upon

a file, it will be capable of receiving and frictionally holding a considerable number of papers and documents under either or both clamping arms and be associated with the case file in a conveniently-handled group which thus forms a file unit from which papers may easily be detached or to which papers may as easily be added without the necessity of taking the clip apart or off the file.

Manifestly, variations may be resorted to and parts and features may be modified or used without others within the scope of the appended claim.

Having now fully described our invention, we claim:

A clip for frictionally securing papers to a file back or the like, said clip comprising a single length of spring metal bent between its ends to define two similar longitudinally elongated co-extensively superimposed arms and a connecting portion, said arms having divergent free ends to facilitate entry of the file back and the papers therebetween, said arms being tensioned toward each other to frictionally engage papers positioned between one of said arms and the file back, and a bendable prong on one of said arms near said connecting portion arranged to be passed through the file back and through an opening formed in the other of said arms near said connecting portion and bent along said other arm whereby said clip is fixed in position on the file back and said arms are held in frictional engagement with the file back and papers inserted between said file back and said one arm.
